UNITED STATES PATENT OFFICE.

WALTER S. TAYLOR AND FRED G. LIADY, OF BREA, CALIFORNIA.

PACKING-SPIDER.

1,151,136.

Specification of Letters Patent. Patented Aug. 24, 1915.

Application filed July 20, 1914. Serial No. 852,083.

To all whom it may concern:

Be it known that we, WALTER S. TAYLOR and FRED G. LIADY, citizens of the United States, both residing at Brea, in the county 5 of Orange, State of California, have invented a new and useful Packing-Spider, of which the following is a specification.

Our invention relates to oil wells and particularly to casing head packers for such 10 wells.

It is common practice in oil wells, especially those of the California and similar fields to form the wall of the well in whole or in part by means of a casing which may 15 or may not be sealed in place but which is ordinarily gas tight and which extends down into the well often to a point near the bottom thereof. Centrally located in this casing is a line of tubing of small diameter 20 which may carry a pump barrel at its lower end and through which the pump rods for actuating the pump in said barrel ordinarily pass. In gaseous wells the gas pressure is often utilized to assist in causing the 25 well to flow or pump and it is common practice to provide a casing head which is rigidly secured to the casing and through which the tubing may pass.

The principal object of the present invention 30 is to provide a packing spider of simple form and construction for making a tight closure between the tubing and the casing head.

A further object is to provide such a packing spider which will be of relatively simple and few parts which may be readily removed whenever desired.

A further object is to provide means whereby the weight of the tubing itself is 40 utilized to keep the packing spider tight.

Referring to the drawings which are for illustrative purposes only: Figure 1 is an elevation, partly in section, of a device embodying our invention, the parts of an oil 45 well being shown diagrammatically. Fig. 2 is a plan view of a portion of the device shown in Fig. 1, the tubing being shown in section. Fig. 3 is a sectional elevation of the casing head with its coöperating parts 50 in place on the tubing and casing, taken on the plane x^3-x^3 of Fig. 2. Fig. 4 is a perspective view of one of the follower rings. Fig. 5 is a perspective view of a spring ring. Fig. 6 is a perspective view of a single pack-

ing member. Fig. 7 is a cross section on 55 the plane x^7-x^7 of Fig. 3.

Referring to the drawings, 10 is a line of casing which is supported in the well partly by the walls of the well and partly by a casing support 11 located on the floor 12 of 60 the derrick of the oil well. The casing support 11 is fastened about the casing under a collar 13 in which is secured a nipple 14 upon which the casing head 15 is tightly screwed. The casing head 15 has a central 65 bore 16 slightly larger than the tubing 17 which extends upwardly therethrough. A circular recess 18 is cut in the upper part of the casing head 15 terminating at its upper end in a slightly beveled portion as shown 70 at 19 and terminating at its lower end in a shoulder 20. Seated on the shoulder 20 is a follower ring 21 formed in two halves as shown in Fig. 4. Upon the ring 21 is placed a series of packing members or rings 22 and 75 a follower ring 21 is placed upon the uppermost packing ring 22. Both the rings 21 and the packing members 22 have a groove 23 cut around the outer surface thereof and each of the same is provided with a spring 80 ring 24 snapped in place in the said groove tending to hold the spring rings and the packing rings respectively together. A follower 25 is provided which consists of a sleeve having a reduced lower end 26 which 85 rests on the upper follower ring being removably secured to the tubing 17 by means of sectional wedges 27. Gas pipes 28 are connected into an annular chamber 29 in the casing head 15 below the packing and 90 are provided with valves 30 through which the gas pressure may be relieved. A gage 31 is provided for the purpose of indicating the exact pressure in the top of the casing. The gage 31 is in open communication with 95 the chamber 29 through a pipe 32.

The method of operation of the invention is as follows: The casing being partly supported by the walls of the well and partly by the casing support 11 the casing head 15 100 is secured thereon and the tubing 17 is lowered into place, being suitably supported temporarily from the upper end by any of the well known means. The packing and split rings are dropped in place and the 105 spring rings are placed upon the respective rings. The follower 25 is then allowed to slide down into the position shown in Fig. 3.

of the drawings and the wedging slips 27 are placed in the upper end of the follower between the same and the tubing tightly locking the follower to the tubing. The 5 temporary supporting means is then gradually released allowing the weight of the tubing to rest on the follower by means of the wedging slips 27 which compress the packing members and make a gas tight joint 10 between the casing head and the tubing, it being understood that the tubing so supported is of considerable length and weight. By regulation of the valves 30 a gas pressure may be maintained in the chamber 29 15 and the space between the casing and the tubing, thereby causing all of the flow of the oil from the well to be directed through the tubing.

We claim as our invention:

- 20 1. A packing spider for oil wells comprising a casing head tightly secured to the top of the casing and having an opening through which the tubing passes, packing means around the tubing inside a recess 25 in said casing head, and means for causing the weight of the tubing to compress said packing.
- 20 2. A packing spider for oil wells comprising a casing head tightly secured to the top 30 of the casing and having an opening through which the tubing passes, packing means around the tubing inside a recess in said casing head, a follower for compressing said packing, and means for causing the 35 weight of the tubing to rest on said follower.
- 30 3. A packing spider for oil wells comprising a casing head tightly secured to the top of the casing and having an opening through 40 which the tubing passes, packing means around the tubing inside a recess in said

casing head, a follower for compressing said packing, and a series of sectional wedges for securing the tubing to said follower.

4. A packing spider for oil wells comprising 45 a casing head tightly secured to the top of the casing and having an opening through which the tubing passes, packing means around the tubing inside a recess in said casing head, a follower loosely surrounding 50 said tubing resting on said packing and provided with a frusto-conical opening in the top, and sectional wedges in said frusto-conical opening bearing on and gripping 55 the tubing.

5. A packing spider for oil wells comprising 60 a casing head secured to the upper end of the casing of an oil well and having an opening therethrough slightly larger than the tubing, said opening being enlarged into a packing recess near the top, packing in 65 said recess, and a follower resting on said packing and supporting the tubing.

6. A packing spider for oil wells comprising 70 a casing head secured to the upper end of the casing of an oil well and having an opening therethrough slightly larger than the tubing, said opening being enlarged into a packing recess near the top, a series of packing rings each having a circular groove 75 in its periphery in which a retaining ring is placed, and a follower resting on said packing and supporting the tubing.

In testimony whereof, we have hereunto set our hands at Anaheim, California, this 75 11th day of July, 1914.

WALTER S. TAYLOR.
FRED G. LIADY.
